UNITED STATES PATENT OFFICE.

DANIEL HANDELAN, OF MINNEAPOLIS, MINNESOTA.

VAPOR-BATH ATTACHMENT FOR BATHTUBS.

Application filed February 14, 1925. Serial No. 9,130.

My invention relates to vapor bath attachments for bath tubs and has for its object to provide a device which may be readily attached to existing bath tubs to enable the 5 user to secure a Turkish or vapor bath therein.

Another object of the invention resides in providing a removable cover or closure for the top of the bath tub, thru which the user's 10 head may protrude while he is taking the bath and which may readily be removed when not in use and for the purpose of giving access to the tub.

A still further object resides in providing 15 a support secured to the faucets of the bath tub and to pivotally mount said closure thereon so that the same may be swung upwardly and out of the way when not in use and may be quickly dropped in place when 20 desired to form an effective closure for the top of the tub to prevent the escape of vapor into the room.

Another object of the invention resides in providing a vaporizing device in conjunction 25 with the bath tub faucets by means of which the hot water ordinarily supplied thereto may be converted into hot water vapor.

Other objects of the invention reside in the specific construction of the same as disclosed in the specification claims and drawings.

In the drawings illustrating my invention in one form:

Fig. 1 is a plan view of my invention.

Fig. 2 is an elevational sectional view of the structures shown in Fig. 1 taken on line 2-2 of Fig. 1.

Fig. 3 is a side elevational view of a modified form of my invention.

Fig. 4 is a side elevational view of a portion of a bath tub illustrating the faucets and showing the manner of applying my invention thereto.

Fig. 5 is a front elevational view of the structure shown in Fig. 4.

Fig. 6 is a view similar to Fig. 4, illustrating a modified form of the invention.

Fig. 7 is a plan view of the structure shown in Fig. 6.

In conjunction with vapor bath attachments for bath tubs, it is highly desirable to have a device which may readily be fitted to the top of the tub so as to form a tight closure therefore and which may be readily raised and replaced to give access into the tub, without causing undue annoyance and to

further provide a structure which will remain in place while the device is in use.

My invention is particularly adapted to function in this manner as will become apparent from the following specification and claims.

In the drawings I have illustrated an ordinary bath tub A which rests upon legs 10 and is provided with the usual water supply lines 11 to which is connected a combination faucet C which will be later described in detail. The bath tub A is formed with a body 12, having a rolled rim 13 extending completely around the edge thereof in the 65 usual manner. Altho I have described a bath tub having a rolled rim, it can readily be understood from the following description that the invention may be equally as well used with any type of tub.

The invention consists primarily of a closure indicated at B which is hingedly connected at one end to a support D held in place thru the agency of the faucet C.

The closure B comprises a flexible cover 80 member 14 which may be made of fabric, rubberized or waterproof material which will permit the same to be folded as desired. This cover member is shaped substantially the same as the rolled rim 13 of the tub and 85 is of such a size that when the closure is placed upon the tub, the edge thereof falls along the center of the rim 13, thruout its length. Along the edge of said cover 14, the same is formed with a hem 15, which is cut 90 away at 16, 17, 18 and 19 for a purpose to be presently described. Within this hem are placed four reinforcing band members 20, 21, 22 and 23 which when connected together form a rigid frame for supporting the fabric 95 cover 14. In the center of the cover, 14 is provided an opening 38 thru which the user may project his head when the device is in use. This opening is connected with a placket 39 for facilitating the insertion of 100 the users head thru the said opening. A number of buttons 40 or equivalent fastening devices may be used to close the placket 39 and provide a snug fit of the cover 14 around the user's neck. It is to be understood 105 that the cover may be made full enough so that the user may have sufficient freedom and latitude of movement to meet with the requirements.

The band member 22 has a sleeve 24 attached to it in which the corresponding end of the band member 23 is adapted to be in-

serted. This sleeve is positioned in the cut away portion 19 of the hem 15 thru which it is accessible and serves to detachably secure these members together. The band members 22 and 21 and the band members 23 and 20 are hingedly connected together at 25 and 26 to permit the entire closure to be folded across its middle and doubled up as clearly shown in full lines in Fig. 2.

10 The structure for supporting the entire closure B upon the tub is illustrated in detail in Figs. 4 and 5. The combination faucet C, there illustrated may be of the type having two bibs 27 and 28 mounted 15 in a single housing 29 which is connected to the water pipes 11 in the usual manner. This faucet is formed with two threaded portions 30 extending thru the tub proper upon which two nuts 31 are screwable and 20 by means of which nuts the faucet may be tightly drawn up against two collars 32 formed thereon, to bear against the tub proper. The support D in the form of the invention shown in Figs. 4 and 5, comprises a plate 33, thru which the threaded portions 30 of the faucet C extend. This plate is adapted to be clamped up tight against the tub proper when the nuts 31 are tightened and thus held in place. The 25 said plate is bent to conform to the contour of the tub proper being curved at 34 to fit along the rim proper 13. At the end of the support D the same is bent over to form a hinge 35 which supports the closure 30 B. This is accomplished by bending the 35 ends 36 and 37 of the band members 21 and 20 towards each other as shown in Fig. 5 and by making the opening of the hinge 35 of such a size that said ends may be readily inserted therein to hingedly connect the closure B to the tub. The ends 36 and 37 may be easily spread apart sufficiently to 40 permit of insertion into said hinge 35, by sliding the hem 15 along the band members 45 20 and 21. It will be noted that the hinge 35 falls in the cut away portion 16 of hem 15, which permits of the attachment of said closure A to the support D and at the same time permits of the entire closure swinging 50 on said hinge.

When the device is collapsed the band members 20, 21, 22 and 23 are completely removed from the hem 15. In use these bands are slid into said hem and the ends 55 of the band members 22 and 23 secured to one another by means of the sleeve 24. After this has been accomplished the ends 36 and 37 are inserted into the hinge 35 after which the device is ready to be used. Before 60 the user steps into the tub the entire closure B is folded back as shown in full line in Fig. 2 which gives easy access into the tub. As soon as the user is seated within the tub closure B can be folded back until 65 it rests thruout its entire edge upon the

rolled rim 13 of the tub proper, forming a relatively tight closure therefor.

For producing the vapor within the chamber formed within the tub and closure A I employ a particular type of faucet having 70 a third bib 41 controlling the flow of water either thru the discharge nozzle 42 or thru a separate discharge neck 43. Such structures being known in the art I have not described the same in detail. Upon the end 75 of the neck 43 is attached a vaporizing nozzle 44 which is adapted to convert hot water from the faucet C into a finely divided vapor or mist and discharge it into the tub. By regulating the bibs 27 and 28 any degree 80 of temperature may be maintained within the tub. With this arrangement it will be unnecessary to have live steam available as the same results can be produced with the hot water.

If desired the hinges 25 and 26 in the closure B may be dispensed with and the band members 21 and 22, and band members 20 and 23 formed integral. Such a construction is shown in Fig. 3 illustrating the closure in its operative position in full lines and in its raised position in dotted lines. The construction of the closure is somewhat simplified in this form of the invention, the closure when raised extends considerably up in the room.

In Figs. 6 and 7 I have shown a modified form of the support D. This device is here illustrated as a casing having two uprights 45 provided at their lower ends with clamps 46 by means of which the same may be securely attached to the combination faucet C without removing said faucet. Upon the upper ends of said uprights is cast a soap tray 47 which extends up above the bib 41 and over and upon the roller rim 13 of the tub A. Immediately above the center of the rim 13 on the rear of said tray 48 is cast two lugs 49 and 50 which are drilled at 51 for the reception of the ends 36 and 37 of the band members. These lugs take the place of the hinge member 35 of the other type of support and serve to hingedly support the closure B in the same manner as with the other type of the invention.

My invention is particularly advantageous, in that a neat and simple construction is secured which operates effectively and efficiently. The device is easily attached to the supporting member and when so attached drops down in place upon the tub in the proper position. When it is desired to raise the same to secure access into the tub, the entire structure may be swung on the hinge where it is out of the way and may be permanently left if desired.

Having described my invention in the form which I consider the best embodiment thereof, I desire to have it understood that the invention may be put to other uses and

constructed in different ways from that shown, within the scope of the following claims.

I claim:

5. 1. In combination with a bath tub having a faucet, a support mounted upon and carried by said faucet, a closure hinged at one end to said support, said closure having an opening thru it at the end opposite said support.

10. 2. A closure for bath tubs comprising a support, hinge means on said support having a transverse opening, a looped frame having the ends thereof facing one another and being adapted to be inserted into said opening from the both ends thereof to form a hinge, and a flexible cover attached to said frame.

15. 3. In combination with a bath tub having a faucet, and a rim extending around the same, a support mounted on said faucet and extending upwardly therefrom a part of said support extending rearwardly therefrom and over a portion of said rim, hinge means formed on the rearward side of said support,

a wire frame conforming in configuration to 25 said rim and adapted to lie upon said rim, said frame having its ends turned towards one another, and adapted to be inserted into said hinge means, and a flexible cover attached to said frame.

30. 4. In combination with a bath tub formed with a rim and having a faucet attached to a wall thereof, a support secured to said faucet and extending upwardly therefrom and along the wall of said tub to which said faucet is attached, said support having a part extending over and upon said rim, and a closure adapted to lie upon said rim and detachably mounted in the part of said support overlying said rim.

35. 5. In combination with a bath tub having a faucet, a support attached to said faucet, said support having a portion lying above the rim of said tub, and a closure for said tub detachably mounted in the portion of 40 said support lying above said rim.

In testimony whereof I affix my signature.

DANIEL HANDELAN.
